UNITED STATES PATENT OFFICE.

RALPH G. BARNES, OF SYRACUSE, NEW YORK.

SASH-CORD FASTENER.

SPECIFICATION forming part of Letters Patent No. 515,186, dated February 20, 1894.

Application filed May 31, 1893. Serial No. 476,064. (No model.)

To all whom it may concern:

Be it known that I, RALPH G. BARNES, of Syracuse, in the county of Onondaga, in the State of New York, have invented new and useful Improvements in Sash-Cord Fasteners, of which the following, taken in connection with the accompanying drawings, is a full, clear, and exact description.

This invention relates to sash chain fasteners, and particularly to the bracket which is secured in the sash and the means for securing the cord or chain thereto.

My object is to produce a sash chain fastener, cheap in construction, positive in its operation, durable and of great utility and to that end my invention consists in the several new and novel combination of parts herein-after described and specifically set forth in the claims hereunto annexed. It is constructed as follows, reference being had to the accompanying drawings, in which—

Figure 1, is an edge view of a window sash, provided with my attachment, and having a sash chain secured thereto. Fig. 2, is a side view of the sash and casing; the sash being broken away to show the position of the device in use. Fig. 3, is a view of the fastener and chain attached. Fig. 4, is a view of the parts, detached.

30 A, is the sash provided with a circular or semi-circular opening —a— in its edge and leading therefrom, vertically, is a groove —b—, the said sash being adapted to travel in the casing —B— in the ordinary way.

35 C, is a semi-circular bracket constructed substantially as shown, having a base or disk

—c— and a flange —d— extending at substantially right angles thereto, and having its ends —e— extending inwardly as shown. The disk or base —c— and the flange —d— 40 are perforated as shown at —f— for the purpose of receiving the link of the chain, or the end of the cord, as desired.

g, is a curved piece of wire or metal adapted to be passed through the link or secured 45 to the chain after it has passed through the perforation —f— and is adapted to rest within the bracket, having its ends abut against the inner faces of the ends of the flange —d—.

What I claim as my invention, and desire 50 to secure by Letters Patent, is—

1. The herein described bracket for a sash chain fastener comprising a base, a flange extending therefrom said flange having inwardly extending ends and said base and flange being perforated at a point of intersection. 55

2. The herein described sash chain fastener comprising a bracket consisting of a base, a flange extending therefrom, said flange having inwardly extending ends, said base and flange being perforated at a point of intersection, and a curved piece of metal adapted 60 to rest upon said base and having its ends abut against the inwardly extending ends of 65 the flange.

In witness whereof I have hereunto set my hand this 22d day of May, 1893.

RALPH G. BARNES.

In presence of—

C. B. KINNE,

HOWARD P. DENISON.
